UNITED STATES PATENT OFFICE.

MATTHEW M. STRICKLER, OF OVERBROOK, PENNSYLVANIA.

DESIGN FOR A HAIR-PIN.

48,162.

Specification for Design.

Patented Nov. 16, 1915.

Application filed August 12, 1914. Serial No. 856,499. Term of patent 14 years.

To all whom it may concern:

Be it known that I, MATTHEW M. STRICKLER, a citizen of the United States, residing at Overbrook, Montgomery county, and State of Pennsylvania, have invented a new, original, and ornamental Design for Hair-Pins, of which the following is a specification, reference being had to the accompanying drawing, forming part thereof.

Figure 1 is a plan view of a hairpin illustrating my new design, and Fig. 2 is an edge view thereof.

I claim:

The ornamental design for a hair pin, as shown.

MATTHEW M. STRICKLER.
